United States Patent Office.

HERMAN WOCHER AND BENENDIKT GEIGER, OF PHILADELPHIA, PENNSYLVANIA.

Letters Patent No. 72,767, dated December 31, 1867.

IMPROVED CURTAIN-FIXTURE.

The Schedule referred to in these Letters Patent and making part of the same.

TO ALL WHOM IT MAY CONCERN:

Be it known that we, HERMAN WOCHER and BENENDIKT GEIGER, of the city and county of Philadelphia, and State of Pennsylvania, have invented a new and useful Improvement in Curtain-Fixtures; and we do hereby declare the following to be a full, clear, and exact description of the same, reference being had to the accompanying drawing, which is made a part of this specification.

The subject of our invention is a device for operating the curtain, and sustaining it at any desired point by means of a weight attached to the curtain-cord, and sliding on a guide-rod attached to the window-frame; and this improvement consists in combining with the weight a spring compressed within it, which presses against the guide-rod, and by its friction renders the weight capable of counterbalancing a much heavier curtain than it could otherwise, while it also, by supporting the weight, renders it capable of operating a curtain otherwise too light.

In the drawing, our invention is illustrated by a perspective view of the inside of a window with our improved fixture applied, a part of the weight being broken away to more fully show its construction.

A represents the curtain, B the cord by which it is operated, and C the weight attached to the end of said cord, and sliding on the rod D, which is attached to the window-frame by spurs $\mathcal{A}$ $\mathcal{D}'$ driven into the sill and jamb. The weight C has an opening through it, corresponding with the rod D on which it slides, and a smaller orifice for the attachment of the cord B, the end of which is knotted within the recess c, in which a spring, E, is located. This spring bears against the side of the bar, and increases the resistance of the weight to the movement of the curtain, thus enabling it to support a much heavier curtain than it could otherwise, while it steadies the movements of the weight, and renders the weight more easily adjusted to different sizes of curtains. By making the rod D angular, the weight is prevented from turning on it, and a better bearing-surface for the spring E is presented.

Having thus described our invention, what we claim as new, and desire to secure by Letters Patent, is—

The spring E, in combination with the hollow weight C and guide-rod D, substantially as and for the purpose set forth.

To the above specification of our improvement in curtain-fixtures, we have signed our hands, this 19th day of September, A. D. 1867.

HERMAN WOCHER,
BENENDIKT GEIGER.
